SIGN AND METHOD OF PRODUCING THE SAME

Rowland N. Chubb, Los Angeles, Calif.

Application November 5, 1932. Serial No. 641,405

6 Claims. (Cl. 40—133)

This invention has for its object the improvement of the device disclosed in my Patent No. 1,755,315, dated April 22, 1930, in which solid-bodied glass members are disposed and more or less loosely held in a perforated metal face-plate. For in-door use, these devices have proved quite satisfactory; but for out-door use, and especially if subjected to vibrations, they are improved if made by the method hereinafter described, in which the glass members are held securely and permanently within the perforations of the face-plate.

By my improved method, I am able to provide a product which is capable of withstanding all degrees of temperature and all chemical conditions to which it may be subjected when employed for its intended purposes, and of withstanding wear, tear and vibrations of every description. Being substantially unaffected by both physical and chemical conditions, it is not only practically indestructible when used in any legitimate manner, but it retains its pristine beauty and brilliance indefinitely. Moreover, it is easily and economically produced.

In the following specification and in the accompanying drawing, I shall disclose the invention in its relation to signs, and particularly to illuminated signs, although it is obvious that it is not restricted thereto, but is capable of employment to give ornamental effects in the production of articles of various kinds, as will more clearly appear hereinafter.

In an illuminated sign, such as is disclosed in my before-mentioned patent, a perforated face plate is employed, the usual practice being to arrange the perforations relatively close together and in such order as to outline the character, symbol, emblem, pictorial device or any design which is to be displayed. This face plate is coated with enamel on both of its faces. Then the glass elements, of any color or any variety of colors, are placed within the perforations and are retained therein by some suitable means. This invention relates specifically to the means for and method of retaining these elements.

In my improved sign, I employ a perforated face-plate of any suitable material, but preferably of sheet metal, and the same is coated on both of its sides with a suitable vitreous enamel. I then place the glass elements in the perforations, as before; but, instead of securing them in place by any old method, as by mechanical means, I simply place the plate, with the elements positioned thereon, in a suitable oven or furnace and apply heat until a temperature is

reached which results in an incipient fusion of some or all of the component parts where they are in contact. This result having been attained, the face-plate is removed from the oven, or the heat is cut off; and, upon cooling, all the parts are as rigidly attached as if they had been cast together in a mold. In some cases it may be desirable to apply some suitable flux to the enameled face-plate, one effect of which would be to bring about the incipient fusion at a lower temperature.

Advantages of my invention, other than those above referred to, will appear hereinafter.

In the accompanying drawing, which illustrates two specific forms of my invention, Fig. 1 is a side elevation showing a fragment of the perforated face-plate of a sign; Fig. 2 is a cross-section, on an enlarged scale, through the face-plate, as on the line 2—2 of Fig. 1, showing the enamel coatings and indicating some of the enamel within the perforation; Fig. 3 is a view similar to Fig. 2, but showing the glass element in the position it occupies before heat is applied, the element being shown in elevation and as having a diameter that is slightly greater than that of the perforation; Fig. 4 is a view like Fig. 3 but showing the positions of the parts after heating; Fig. 5 is a view like Fig. 4 except that it is on a larger scale and shows the element in section; Fig. 6 is a view, similar to Fig. 4, showing a modified structure produced by a modified method; Fig. 6A is a view showing a portion of Fig. 6 on an enlarged scale, and Fig. 7 is a plan view of a portion of a sign embodying my invention and having a source of illumination 90 therein.

Referring to the drawing, 10 represents the metal face-plate in which perforations 11 are so positioned as to form the desired design. This plate is coated on both of its sides with a suitable vitreous enamel 12. In applying these coatings, the enamel enters the perforations to a slight extent, as indicated in Fig. 2, so that the openings through the coatings are of slightly less diameter than the perforation in the metal. 100

The elements, indicated at 13, are usually of transparent material and are preferably glass beads or spheres. These may be, and usually are, vari-colored, which enhances the ornamental effect. When the object to be represented is in 105 various colors, the elements used will be of corresponding colors, as will be understood. If a solid background in color is desired, the plate will be perforated throughout all the area of the background, and elements having the ap- 110

properite color will be used therein. The sizes of the perforations and elements will be varied according to the nature of the design to be shown. For example, if the design is large and 5 mono-chromatic, the elements may be relatively large; whereas, if it be multi-chromatic, as a bouquet of variously colored flowers, the elements will be relatively small.

The elements are, by preference, slightly larger 10 than their respective perforations so that they will not quite pass through them; and, in my preferred form, when they are first placed on the face-plate, as in Fig. 3, they rest on the enamel, the opening in which is somewhat smaller than 15 the perforation. With all the elements positioned as in Fig. 3, the face-plate, with the elements on its upper surface, is placed within an oven or furnace and the temperature is raised to a white heat, thereby causing the glass of the 20 elements and the enamel to soften and to undergo an incipient fusion, with the result that the elements settle down and become slightly distorted as they enter farther and farther into the perforations, as shown in Fig. 4. If left too long 25 in the intense heat, the elements will drop through the plate. Care is to be taken, therefore, to remove the plate from the oven or furnace or to cut off the heat when the elements have reached a substantially mid-position, as 30 shown in Figs. 4 and 5. Elements having sizes which are equal to or even slightly less than the perforations may be used if they rest on the enamel, as in Fig. 3, and if sufficient care be taken not to allow them to pass into the perforations beyond the mid-position. However, I prefer to use the larger elements, since they become 35 more firmly secured and require less care in heating.

As the partially molten glass and enamel cool 40 they coalesce and form a unitary body which completely envelopes and hermetically seals the plate, thus protecting it from the air and from all deleterious fumes and substances. Fig. 5, which is a section through one of the elements, shows how the enamel and glass of the 45 elements coalesce and envelop the plate. As has been stated, a suitable flux may be used, if desired, to lower the temperature at which incipient fusion takes place.

50 In Figs. 6 and 6A, I have shown a modified structure in which 10A represents the perforated plate, 14 a decorative coat of colored lacquer or the like and 13A the element. In this structure the perforation is preferably of slightly greater 55 diameter at one side of the plate than it is at the other which results in a tapered wall about the perforation, as indicated at 15 in Figs. 6 and 6A. The element is somewhat larger than the 60 perforation at its smallest part so that it rests in approximately mid-position, as shown.

In making up the structure shown in Figs. 6 and 6A, I first apply what I shall term a decorative coating 14 composed of a suitable lacquer or the like having the desired color or colors. 65 This coating not only covers the exterior surfaces of the plate, but enters slightly into the perforations in a manner similar to that shown in Fig. 2 where the enamel is shown as slightly entering the perforations. I then dip the elements which are to be used in a clear or substantially transparent lacquer or cement and place them in their respective perforations. The lacquer on the elements contacts with the lacquer of the decorative coating at the perforations, softens it, and actually coalesces with it. 75

The elements are then pressed into their perforations to approximately their mid-positions. To hold the elements more securely in position, I then apply on both sides of the plate in any suitable manner, as by spraying, a coating 16 of the clear and substantially transparent lacquer, said coating covering not only the decorative coating but also the elements as shown. Since the coating 16 is transparent, it will not interfere with the transmission of light nor will it dim the brilliance of the elements.

80 The coating 16 is shown greatly exaggerated in thickness as it is a mere film, particularly over the elements; but it fills in all interstices about the latter and completely seals the plate and the elements and thus holds the latter in place and also protects the plate from the air and other harmful agents. In this form of my invention, no heat is necessary in fixing the elements in position. In both forms, however, the plate is protected by an sealing coating. It is this coalescence of the cement coating 16 with the decorative coating 14 and its adherence to the elements which cause the elements to be retained in position. This is believed to be a 95 new means for holding the elements in a face-plate.

90 It will be understood that the sign may be so used that the design appears by reflected light only. In such a case, the many colored elements 105 give very pleasing effects, whether used in connection with a sign or for ornamentation of other devices. But greater brilliance is secured when the light is transmitted through the colored elements. In Fig. 7, I have shown a portion of a 110 sign in which a light emitting source, as an electric bulb 17, is placed at the rear of the face-plate 10 so that the light passes through the elements 13, as will be understood.

115 While I have shown and described certain details of structure and method, it is realized that these details are susceptible of variation without departure from the spirit of my invention, and I desire it to be understood that the following claims are not intended to be limited to such details any farther than is necessitated by the specific terms therein employed.

120 Having thus described my invention, I claim:

1. A sign or the like comprising a face plate having a plurality of perforations therein, the walls of the perforations being tapered inwardly from the front to the rear of the face plate, a decorative coating of lacquer covering the front side of said plate and extending to the perforations therein, vitreous elements within said perforations, said elements being slightly larger than their respective perforations at the rear side of the plate, and a coating of transparent lacquer covering the said elements at the front of said plate, coalescing with the said decorative coating 135 and serving to hold the elements in position.

2. A sign or the like comprising a face plate having a plurality of perforations therein, a coating of lacquer on each side of the plate and extending to the said perforations, lacquered beads 140 within the said perforations, the lacquer of the beads being coalesced with the lacquer coatings and an outer coating of lacquer covering the outer surfaces of the beads and extending over the lacquer coatings on the sides of the plate, said 145 outer coatings being coalesced with the lacquer coatings of the plate and helping to retain the beads in their respective perforations.

3. An illuminated sign or the like comprising a face plate having a plurality of perforations there- 150

- in, said perforations being smaller at the rear side of the plate than at the front side, a decorative coating of lacquer covering both sides of the plate and extending to the perforations therein, 5 spherical glass beads in said perforations, said beads being slightly larger than the perforations at the rear side of the plate and resting upon the restricted walls of their respective perforations, an outer coating of transparent lacquer covering 10 those parts of the beads which project beyond the plate, overlapping and coalescing with the decorative coating and holding the beads in place, and a source of illumination at the rear of the face plate.
- 15 4. The method of producing a sign or the like which comprises providing a face plate with a plurality of perforations, applying a coating of decorative lacquer to the front face of said plate, placing a glass element in each of said perforations and applying an outer coating of transparent lacquer, said outer coating covering the projecting portions of said beads, coalescing with the lacquer of the decorative coating and holding the beads in position.
- 20 5. The method of producing a sign or the like which comprises providing a face plate with a plurality of perforations coating both sides of the plate with lacquer, immersing glass beads in transparent lacquer and placing them while wet with the lacquer in the respective perforations thereby causing the lacquer thereon to coalesce with the lacquer of the decorative coatings, permitting the lacquer to dry, and then applying an outer coating of transparent lacquer over the plate and over the beads, whereby the said outer coating coalesces with the lacquer on the beads and on the plate and thus secures the beads in position. 80
- 25 6. The method of producing a sign or the like which comprises providing a face plate with a plurality of circular perforations which taper inwardly from the front to the rear side of the plate, applying a coating of lacquer to both sides of said plate with the lacquer extending to the perforations therein, immersing glass beads in transparent lacquer, pressing said beads while wet with the lacquer into their respective perforations and causing the lacquer thereon to coalesce with the lacquer on the sides of the plate, permitting the lacquer to dry and then applying an outer coating of transparent lacquer over the beads and plate to cause the lacquer of the outer coating to coalesce with the lacquer on the beads and plate, 90 95 100 for the purpose specified.
